PROTECTING SHIELD

Douglas L. Craddock, Leaksville, N. C.

Application April 3, 1951, Serial No. 218,959

5 Claims. (Cl. 128—132)

1

This invention relates to safety or sanitary protecting devices particularly for preventing spread of venereal diseases, and in particular a shield having a centrally disposed opening with straps extended from the corners for attaching the shield to the body and having an annular flange extended around the opening and positioned in a plane parallel to the face of the shield whereby the open end of a tubular element may be wrapped over the flange and secured under the outer edge thereof to prevent the spread of disease germs on the interior of the sleeve to the outer surface thereof.

The purpose of this invention is to provide means for mounting a shield on the inner end of a sanitary protecting device to prevent the spread of disease germs from the elements.

In the conventional type of tubular protector it is possible for germs to work around the open end and reach the outer surface whereby the germs may spread to a second party. With this thought in mind this invention contemplates an extended shield in which the open end of the tubular element is secured whereby the area around the organ on which the tube is used is protected.

The object of this invention is, therefore, to provide means for mounting a sanitary or protecting shield around the open end of a tubular protector whereby with the shield mounted by straps extended therefrom on the body the tubular element is secured in position and disease germs therefrom substantially isolated.

Another object of the invention is to provide a sanitary shield for the open inner ends of tubular protectors that may be attached to protectors of the conventional type.

A further object of the invention is to provide an enlarged protecting shield for tubular protecting devices which is of a simple and economical construction.

With these and other objects and advantages in view the invention embodies an extended shield of flexible material with one strap extended from the upper end adapted to be positioned around the body, with two straps extended from the lower end and adapted to extend around the legs of the body and with an opening having an annular mounting flange extended therearound and on which the open end of a tubular element may be mounted.

Other features and advantages of the invention will appear from the following description taken in connection with the drawings, wherein:

Figure 1 is a front elevational view of the pro-

2

tector with the tubular element shown in section.

Figure 2 is a cross section through the central section of the protector taken on line 2—2 of Figure 1 showing the connection of the tubular element to the protector with the parts shown on an enlarged scale.

Figure 3 is a detail on an enlarged scale illustrating the method of holding the open end of the tubular element in the opening of the shield.

10 Referring now to the drawings wherein like reference characters denote corresponding parts the protector of this invention is formed with a shield 10 having an opening 11 centrally positioned therein with a bead 12 surrounding the opening and with an annular mounting flange 13 also around the opening and spaced therefrom, and also with straps 14, 15 and 16 for holding the shield in position extended therefrom.

One end of the strap 14 is secured by a strap fastener 17 to one corner of the upper end of the shield and the opposite end is secured by snap fastener elements 18 and 19 to the opposite corner of the upper end of the shield.

The straps 15 and 16 are formed integral with the shield 10 and the ends of the straps are provided with snap fasteners 20 and 21 that are positioned to coat with similar fasteners 22 and 23, respectively on the lower part of the shield so that the straps may be extended around the legs for retaining the shield in position.

25 The open end of a tubular protector 24 is inserted through the opening 11 with the bead 25 on the edge of the protector extended into a recess 26 behind the flange 13.

30 It is preferred to form the shield, tubular element and straps of rubber although it will be understood that other suitable flexible material may be used.

35 With the tube 24 mounted in the shield 10 in this manner it will be substantially impossible for germs to work from the interior of the tube around the open end thereof to the outer surface.

The tubular element may otherwise be used in the conventional manner, and may be removed and replaced as used.

40 It will be understood that modifications may be made in the design and arrangement of the parts without departing from the spirit of the invention.

45 What is claimed is:

1. A shield having a centrally disposed opening extended therethrough with a bead around the edge of the opening and with an annular flange spaced from the opening and extended outwardly therefrom, said flange positioned in a

3

plane parallel to the plane of the shield, and a tubular protecting element the open end of which is extended through the opening of the shield and the rim of which is positioned over the said annular flange.

2. A shield having a centrally disposed opening extended therethrough with a bead around the edge of the opening and with an annular flange spaced from the opening and extended outwardly therefrom, said flange positioned in a plane parallel to the plane of the shield, a tubular protecting element the open end of which is extended through the opening of the shield and the rim of which is positioned over the said annular flange, and straps having fasteners in the ends thereof positioned to coact with the fasteners on the shield for clamping the shield to the human body.

3. A sanitary protecting shield comprising a substantially rectangular-shaped rubber sheet having a centrally positioned opening therethrough with means around the opening adapted to connect the open end of a tubular element thereto, and having elastic straps extended from the lower corners of the sheet with snap fasteners on the corners of the sheet and ends of the straps and with a strap having snap fasteners on the ends thereof positioned to coact with snap fasteners on the upper corners of the sheet.

4. A sanitary protecting shield having a substantially rectangular shape rubber sheet having a centrally positioned opening therethrough with

4

elastic straps extended from the lower corners of the sheet with snap fasteners on the corners of the sheet and end of the strap and with a strap having snap fasteners on the ends thereof positioned to coact with snap fasteners on the upper corners of the sheet, said sheet having an annular bead around the inner edge of the opening, and an annular flange spaced from the opening and extended outwardly therefrom, said flange positioned with the outer part thereof spaced from the said sheet.

5. A sanitary protecting shield having a substantially rectangular shape rubber sheet having a centrally positioned opening therethrough with elastic straps extended from the lower corners of the sheet with snap fasteners on the corners of the sheet and end of the strap and with a strap having snap fasteners on the ends thereof positioned to coact with snap fasteners on the upper corners of the sheet, said sheet having an annular bead around the inner edge of the opening, an annular flange spaced from the opening and extended outwardly therefrom, said flange positioned with the outer part thereof spaced from the said sheet, and a tubular element extended through the opening of the rubber sheet and positioned with the rim thereof extended under the edge of the rim of the said annular flange.
